FLUID PUMP

Arthur Kosian, Chicago, Ill.

Application May 28, 1938, Serial No. 210,657

1 Claim. (Cl. 103—123)

This invention relates to improvements in rotary fluid pumps and has, for one of its principal objects, the provision of such a pump which shall be simple, compact and economical to manufacture, composed of a minimum of parts, easy of operation and not likely to get out of order.

One of the important objects of this invention is the provision of a rotary fluid pump that has both its inlet and outlet for the fluid in the driven shaft, thereby gaining a uniformity of appearance and mechanical efficiency.

Another object of this invention is the provision of a rotary fluid pump that is self-lubricating especially when it is pumping oil or when it is operating in the capacity of a compressor in a refrigerating system.

Another important object of this invention is the provision of an irregular eccentric rotor operating in conjunction with four double abutments in a surrounding housing to produce the suction and pressure of this fluid pump.

Other and further important objects of the invention will be apparent from the disclosures in the accompanying drawing and following specification.

The invention, in a preferred form, is shown in the drawing and hereinafter more fully described.

30 In the drawing:

Figure 1 is an end view of the pump with the outer casing removed.

Figure 2 is an irregular section taken on the line 2—2 of Figure 1.

35 Figure 3 is the irregular eccentric rotor removed from the pump.

Figure 4 is a detail section of one set of the abutments which are in the housing surrounding the rotor.

40 As shown in the drawing:

The reference numeral 10 indicates generally the outer casing or housing of the improved rotary fluid pump of this invention.

45 Inside the casing 10 is the suction and compression cylinder 12 which houses an irregularly shaped eccentric rotor 14 driven by the shaft 16, the key 18 keeping same in locked relationship.

As best shown in Figure 2, there is on the intake side of the pump a fluid seal 20 which prevents any of the liquid being pumped, from escaping. This fluid seal is held in position by a cap screw bearing 22.

A plurality of sets of double abutments 24 are positioned in slots around the pump casing and

extend into and contact the rotor 14, these abutments being spring-pressed as illustrated at 26.

An inlet channel for oil or other fluid to be pumped is provided at 28, said inlet channel passing into and running longitudinally centrally of the shaft 16 and terminating in a plurality of branches as shown at 30. The fluid is drawn into these inlet channels by the suction created by the irregular rotatable eccentric 14 and is then put under compression by the same eccentric rotor as the abutments 24 operate in closing off said channels. While under compression, the fluid will travel out the outlet channels 32, thence to the center of the shaft again, as at 34, and out. The shaft 16 is so bored that the outlet part 34 is of slightly greater diameter than the inlet part 36. Between these two cavities is positioned a separating wall 38 which enables the intake and outgo of the fluid to be carried through the hollow portion of the shaft. As the fluid is pumped out, some of it communicates with the fittings for the abutments through an auxiliary channel 40 and circular groove 50 in the housing 10, and it is evident that this added pressure of fluid on the outer edges of the abutments 24 will be supplementary to the action of the springs 26 and provide a better operating contact of the inner rounded ends of the abutments 24 with the rotor 14 at points 42.

As best shown in Figure 3, a circular or similarly shaped groove 44 is provided in one face of the irregular eccentric rotor element 14, and a channel 46 leads from one of the outlet ducts 32 to this groove 44. In this manner, the pressure which exists in the outlet portion of the pump is communicated directly, by means of the fluid being pumped, to the channel or groove 44, and the area of this groove 44 is designed to be exactly the same as the area of the end of the driving shaft 16 so that the pressure which is exerted on the end of the driving shaft and the partition 38 during pumping is exactly counterbalanced by a similar pressure existing on the liquid in the groove or channel 44.

Also, in conjunction with this same arrangement is the shoulder 52 formed integral with the outer face of the shaft 16 adjacent the point where the plug 38 is positioned and which abuts against a corresponding shoulder formed in the inner face of the cylindrical opening through the rotor element 14. The existence of this shoulder prevents any tendency toward driving of the shaft 16 rearwardly out of the pump casing 10.

which might otherwise take place on account of the very considerable internal end pressures often built up in a pump of this type.

It will be noted that ninety degrees of the 5 operating surface of the rotor 14 is formed on the arc of a circle having the center of the driving shaft as its center, and the opposite ninety degrees of the periphery of the rotor is also formed on a circle having the same center 10 but with a slightly smaller radius. The two intermediate ninety degree arcs are also circular but are not concentric with the other two surfaces, the joining arcs being so designed as to 15 form as smooth as possible a connection between the first-mentioned arcuate surfaces. The lengths of the arcs may be varied somewhat, as the 90° structure is not critical. The abutments 20 are intentionally placed at an angle to the radius of the pump, this offsetting effecting a better operation on high pressure inasmuch as there is not nearly so great a tendency to side-thrust against the abutments when they are so 25 positioned as to distinguish from a radial positioning, and the ends of the abutments which contact the cammed surface of the rotor need not be forced through a perpendicular motion when the pump is in operation.

As best illustrated in Figure 4, there are two 30 parts in each abutment, there being a projection 48 at the top of each part, this projection being semi-cylindrical in cross-section, and when the two parts are properly positioned with relation to each other, the helical spring 26 surrounds 35 these two semi-cylindrical projections as best shown at 48 in Figure 2, thereby connecting the parts and also affording a satisfactory seat for the lower end of the spring, the upper end of which is positioned in a recess in the casing wall 40 as shown. A one-piece abutment will operate satisfactorily in this connection although it has been found by experience that these double structures effect a better sealing action for a greater length of time.

45 The space between the inner wall of the cylinder 10 and that portion of the rotor having the largest radius can be quite small, and in fact,

the smaller this space the better resultant sealing and pumping action.

All parts of the device are automatically lubricated especially when oil or any liquid containing oil is being pumped, and the apparatus is particularly efficient as a vacuum pump. When operating on liquids, a very steady stream is produced, there being practically no undesirable pulsation, and this together with the compact size of the device and the minimum number of parts make for an ideal apparatus of this type.

This application, particularly with reference to the pump structure, comprises an improvement over the pump portion of my previous application 15 for patent on "Hydraulic clutch and power transmission," filed August 7, 1937, Serial No. 157,889.

I am aware that many changes may be made and numerous details of construction varied throughout a wide range without departing from 20 the principles of this invention, and I, therefore, do not purpose limiting the patent granted hereon otherwise than as necessitated by the prior art.

I claim as my invention:

A rotary pump, comprising a driving shaft, a 25 rotor mounted on the end of the shaft generally eccentric thereto, said rotor having diametrically opposite portions concentric with said shaft but of different radii, a cylindrical housing for the 30 rotor, abutments slidably mounted in the housing walls at an angle to radii thereof, and having their inner ends contacting the rotor, each abutment comprising a pair of rectangular plates, a half round lug integral with the outer edge of each plate, said lugs being juxtaposed to form 35 a two-part cylinder, helical springs seated on the cylinders for impelling the ends of the abutments against the rotor, a fluid inlet channel in the pump shaft, and a fluid outlet channel also in the pump shaft, an auxiliary channel connecting 40 the fluid outlet and the inner ends of the slots in which the abutments are positioned whereby fluid pressure in the outlet means is communicated to the vanes and supplements the spring action thereagainst.

ARTHUR KOSIAN.
